UNITED STATES PATENT OFFICE.

ALEXANDER C. DUMONTIER, OF DETROIT, MICHIGAN, ASSIGNOR OF TWO-THIRDS TO WILLIAM M. DWIGHT AND FRANK M. LILLIBRIDGE, BOTH OF SAME PLACE.

KNIFE FOR PLANING-MACHINES.

SPECIFICATION forming part of Letters Patent No. 389,139, dated September 4, 1888.

Application filed December 22, 1887. Serial No. 258,721. (No model.)

To all whom it may concern:

Be it known that I, ALEXANDER C. DUMONTIER, of Detroit, in the county of Wayne and State of Michigan, have invented a new 5 and useful Improvement in Knives for Planing-Machines, of which the following is a specification.

My invention relates to knives for planing-machines; and it consists in the novel features 10 of construction hereinafter fully described, and then definitely pointed out in the claims.

In the accompanying drawings, Figure 1 is 15 an aside elevation; Fig. 2 an end elevation; Fig. 3, a plan view of the edge of a planing knife; Fig. 4, a perspective view showing the planing-knife in position on a cylinder.

A represents a planing-machine knife provided with the ordinary slots, S S, for bolting the same to a cylinder, and B represents the 20 cutting-edge of the knife. As will be seen in Figs. 1 and 3, this cutting-edge, instead of being parallel with the side surfaces of the knife-bar, which would make it parallel with the sides of the cylinder when the knife is 25 bolted in place, runs diagonally across the end of the knife-bar, either from corner to corner or at a somewhat greater or less angle, as preferred, and it is formed by grinding away the sides of the bar in opposite directions, as shown by the lines C D. Of course 30 when a knife with such an edge is bolted onto a cylinder with the ends of the knife bar at right angles to the axis of the cylinder it is necessary to make one side of the knife bar 35 longer than the other, as shown in Fig. 1, so that all parts of the cutting-edge B will be at the same distance from the center of rotation of the cylinder; or the same result may be attained by making the knife of equal length at 40 each side and bolting it to the cylinder at such an angle therewith that all parts of the cutting-edge B will be in the same rotary plane.

I prefer to make these knives short, and for 45 wide surfaces to fasten them alternately on opposite sides of the cylinder, so as to cover the whole surface of a board in their rotation, rather than to make a single long knife, as in long knives the inclination of the cutting-edge is less than in a short knife.

When the knife A is bolted to an ordinary 50 planing-machine cylinder and is set in rotation, the cutting-edge will not all strike the board simultaneously, as is the case with an ordinary knife; but that portion of the edge which is nearest the surface of the knife in 55 contact with the cylinder will strike the board first and will be followed by the rest of the cutting-edge, thus giving the knife a drawing cut, which causes it to do much smoother work than the ordinary knife, and also enables the 60 feed to be increased without increasing the speed of the cylinder—a desirable result in planing-machines.

I am aware that a cylinder has been placed 65 at an angle across the bed of the planer, and that a cylinder set at right angles with the 70 planer has been twisted, the object in both cases being to set an ordinary knife at an angle with the board to be planed for the purpose of obtaining a drawing cut; but this method requires either a specially-constructed cylinder, or requires an alteration in the gear of a 75 planing-machine, so that it is not adapted for use on ordinary planers as now built, while my invention may be put in any planer whose cylinders are at right angles with the feed 80 without any changes in the gear.

What I claim as my invention, and desire to 85 secure by Letters Patent, is—

1. In combination with the cylinder of a 80 planing-machine placed at right angles across the bed of the machine, a knife having its cutting-edge formed diagonally across the end of the knife-bar, secured to the cylinder with its cutting-edge all in the same rotary plane, substantially as and for the purpose set forth.

2. A planing-machine knife having its cutting-edge B formed diagonally across the end of the knife with respect to the parallel side surfaces of the knife-bar A, said knife-bar being longer on one side than the other, substantially as described.

ALEX. C. DUMONTIER.
